(57) **CLAIM**

I claim the ornamental design for a cleaning tool, as shown and described.

DESCRIPTION

FIG. 1 is a perspective view of an embodiment of the claimed design;

FIG. 2 is a front plan view of the design of FIG. 1;

FIG. 3 is a rear plan view of the design of FIG. 1;

FIG. 4 is a right side plan view of the design of FIG. 1;

FIG. 5 is a left side plan view of the design of FIG. 1;

FIG. 6 is a top plan view of the design of FIG. 1; and,

FIG. 7 is a bottom plan view of the design of FIG. 1.

The ornamental design which is claimed is shown in solid lines in the drawings. The broken lines in the drawings are for illustrative purposes only and form no part of the claimed design. Broken lines formed by equal length dashes show unclaimed portions of the design. Broken lines formed of unequal length dashes (i.e., dash-dot) show boundaries between claimed and unclaimed portions of the designs. Lines having a jagged element are not part of the claimed design and show that no particular length of the portion is claimed.
